UNITED STATES PATENT OFFICE.

MYRON COLONEY, OF NEW HAVEN, CONNECTICUT, ASSIGNOR TO JAMES HENRY McLEAN, OF ST. LOUIS, MISSOURI.

MARINE TORPEDO.

SPECIFICATION forming part of Letters Patent No. 225,465, dated March 16, 1880.

Application filed February 10, 1879.

To all whom it may concern:

Be it known that I, MYRON COLONEY, of the city and county of New Haven, in the State of Connecticut, have invented certain new and useful Improvements in Marine Torpedoes, of which the following is a specification.

My invention relates to torpedoes provided with magnets to cause them to attach themselves to an iron vessel which they may be designed to destroy.

The invention consists in a magnetic appliance for retaining coupled torpedoes in parallel position while passing through the water, as hereinafter explained.

In order that my invention may be fully understood, I will proceed to describe it with reference to the accompanying drawings, in which—

Figure 1 is a side view of a single torpedo, illustrating the first and second parts of my invention. Fig. 2 is a rear view of the same. Fig. 3 is a plan of a pair of coupled torpedoes, illustrating the third part of the invention. Fig. 4 is a perspective view of the coupling devices.

A A represent cigar-shaped submarine boats containing spring or other motive power operating screw-propellers B; by which the said boats are driven through the water. C C are rudder-plates to confine the boats to direct lines of motion.

When the boats are used singly the rudder-plates are crossed in planes at right angles to each other, as shown in Figs. 1 and 2, so that in event of the boat rolling over the steering effect of the rudder-plates will not be impaired.

T represents the explosive shell or torpedo proper, rigidly attached to the prow or forward end of the boat by bars D D.

M M are magnets attached to a hoop, E, fixed to the side of the boat, so that the poles of the magnets will be presented outward and in a circle. M' in Fig. 1 represents magnets attached in similar manner to a hoop, E, sur-

rounding the point of the torpedo T, the poles of the magnets M' being presented forward.

Referring to Fig. 3, F represents a coupling-bar hinged to the prow of each of a pair of torpedoes, as described in an application of James H. McLean, M. D., filed the 30th of July, 1878. G G' are rigid bars projecting from the opposite sides of the two torpedo-boats A A. Between the ends of the bars G G is fixed a magnet, M², and on the ends of the opposite bars, G' G', is fixed a circular iron plate, H, provided with a flange, h, and constituting the armature of the magnet M².

M³ M³ represent a range of magnets pivoted to bars I I; and M⁴ magnets, mounted on the coupling-bar F, as described in the application of Dr. J. H. McLean, above referred to.

In operation, the magnet M² and plate H on the ends of the bars G G and G' G' respectively will hold the boats A A in parallel position until an iron vessel is approached, when the superior attraction of the magnets M or M³ will cause the two boats to be drawn into line and along the side or bottom of the vessel.

It is manifest that this part of my invention may be used without the particular mode of applying the magnets or the rudders described with especial reference to Fig. 1, and, further, that the modes of applying the magnets and the rudders shown in Figs. 1 and 2 may either be used without the other or without the magnetic coupling device shown at M² H in Figs. 3 and 4.

Having thus described my invention, the following is what I claim as new and desire to secure by Letters Patent:

The combination, with a pair of torpedo-boats hinged together, of a magnet, M², and armature H, attached to the respective boats to hold them in parallel position while passing through the water, as explained.

MYRON COLONEY.
